UNITED STATES PATENT OFFICE.

RICHARD ROTHWELL, OF LOS ANGELES, CALIFORNIA.

RAILROAD-CROSSING.

1,338,253.

Specification of Letters Patent. Patented Apr. 27, 1920.

Application filed October 13, 1919. Serial No. 330,453.

To all whom it may concern:

Be it known that I, RICHARD ROTHWELL, a citizen of the United States, residing at Los Angeles, in the county of Los Angeles and State of California, have invented 5 new and useful Improvements in Railroad-Crossings, of which the following is a specification.

My object is to make an improved actuator for a silent railway crossing, and my 10 invention consists of the novel features herein shown, described and claimed.

The present invention is an improvement upon the actuator shown in my Patent No. 15 1,283,672, dated November 5, 1918, for silent railway crossings granted to Charles Clai- born and assigned to myself.

Figure 1 is a fragmentary top plan view 20 of a silent railway crossing and showing the actuator embodying the principles of my invention in use.

Fig. 2 is an enlarged fragmentary top plan view of the actuator shown in Fig. 1 and the view being taken looking in the direction indicated by the arrow 2 in Fig. 3, and parts being broken away and shown in section.

Fig. 3 is a vertical cross section on the irregular line 3—3 of Fig. 2 and looking in 30 the direction indicated by the arrows.

Fig. 4 is an enlarged perspective of the mounting for the actuator with the other parts omitted and the view being taken looking in the direction indicated by the arrow 35 4 in Fig. 2.

Fig. 5 is a fragmentary vertical sectional detail on the line 5—5 of Fig. 2.

The first railway track includes the rails 1 and 2 and the second railway track 40 includes the rail 3 crossing the rails 1 and 2 at right angles. The rail 1 has tread portions 4 and 5. The rail 2 has tread portions 6 and 7. The rail 3 has tread portions 8, 9 and 10. The inner edges 11 and 12 of the 45 tread portions 4 and 5 are in a line to be engaged by a car wheel flange. The inner edges 13 and 14 of the tread portions 6 and 7 are in a line to be engaged by a car wheel flange, and the inner edges 15, 16 and 17 of the tread portions 8, 9 and 10 are in a line 50 to be engaged by a car wheel flange.

A vertical slot 18 is formed through the treads and webs at an angle of 45° relative to the edges 11 and 15, and a similar vertical 55 slot 19 is formed through the treads and

webs at an angle of 45° relative to the edges 13 and 17 and at right angles to the slot 18. The slot 18 separates the portions 4 from 5 and 8 from 9, and the slot 19 separates the portions 6 from 7 and 9 from 10. A tread shifting member 20 is mounted slidingly in the slot 18, and a similar tread shifting member 21 is mounted slidingly in the slot 19.

The shifting member 20 has shifting treads 22 and 23. The shifting tread 22 has an edge 24 adapted to move into line with the edges 11 and 12, and the shifting tread 23 has an edge 25 adapted to move into line with the edges 15 and 16. The shifting member 21 has shifting treads 26 and 27. The shifting tread 26 has an edge 28 adapted to move into line with the edges 16 and 17, and the shifting tread 27 has an edge 29 adapted to move into line with the edges 13 and 14. The shifting members 20 and 21 have corresponding ends connected to links 30 and 31 and the links 30 and 31 are connected together by a pivot 32.

The actuator 33 is connected to the rail 2 and to the pivot 32 to be actuated by a car approaching the crossing in the direction indicated by the arrow 34. The details of the actuator 33 are shown in Figs. 2, 3, 4 and 5.

The actuator mounting 35 has an attaching plate 36 secured against the inner side of the web 37 of the rail 2 by bolts 38. A ledge 39 extends inwardly from the upper part of the attaching plate 36. The ledge 39 has a portion 40, the upper face 41 of which is substantially on a level with the upper face of the tread 6 and has a platform face 42 on a lower level. A recess extends from the platform face 42 into the portion 40 of the ledge to form the actuator seat 43. A second recess extends downwardly from the platform face 42 into the ledge 39 to form a lever seat 44.

A circular bearing recess 45 extends downwardly from the bottom of the lever seat 44 and a pin hole 46 extends from the bottom of the bearing recess 45 through the ledge.

The actuator bar 47 is a flat bar having a straight face 48 and a head 49. The head 49 is rounded to a semicircle to form the bearing face 50 and the head 49 fits in the seat 43 with the face 50 in contact with the face of the seat. A pin 51 extends downwardly from the head 49 concentric to the face 50.

through a pin hole 52 at the bottom of the seat 43. The cotter 53 is inserted through the lower end of the pin 51 below the ledge 39. The flange 54 extends from the ball of the rail 6 inwardly from the edge 13. The ledge 39 has a recess 55 in which the flange 54 fits. The actuator bar 47 rests upon the flange 54 and the edge 48 normally extends diagonally across the flange 54 from the contacting point 56 through the head 49, so that when the car wheel is rolling along the tread 6 with the car wheel flange against the edge 13 the car wheel flange will strike the edge 48 and move the actuator bar 47 inwardly away from the edge 13 as required to allow the car wheel flange to pass.

The lever 57 has an arm 58 connected to the pivot 32 and an arm 59 bearing against the inner face of the free end of the actuator bar 47. The lever 57 has a head 60 fitting in the seat 44, a pintle 61 fitting in the bearing recess 45, and a pin 62 extending through the opening 46. A cotter 63 is inserted through the pin 62 below the ledge 39. The arm 59 extends from the head 60 at an angle of more than 90° relative to the arm 58. A link 64 connects the free end of the actuator bar 47 to the free end of the arm 59, said link being recessed into the lower sides of the parts 47 and 59, there being pins 65 and 66 extending downwardly into the ends of the link to form the pivots.

Assuming that the parts are in the position shown in Fig. 1 and the car is moving in the direction indicated by the arrow 34, the car wheel flange will strike the edge 48 of the actuator bar 47, the pivot 32 will move in the direction indicated by the arrow 67, and the shifting members 20 and 40 21 will be moved to bring the edges 24 and 29 into line with the edges 11 and 13, so that the car wheels will pass the groove 68 upon the treads 22 and 27.

In a like manner the actuator 69 will be operated by the car moving in the direction indicated by the arrow 70 to move the shifting members 20 and 21 to bring the edges 25 and 28 into line with the edges 15 and 17, and then the car will cross the grooves 71 and 72 upon the treads 23 and 26.

If it is desired to make a silent crossing to be operated by cars moving toward the crossing in the four directions there will be four actuators 33 or 69. Where it is only desired to run cars one way upon each track only two actuators will be required. In any event there will be four shifting members 20 and 21 connected together for simultaneous operation.

There is a decided advantage in operating the actuator bar 47 against the arm 59 and connecting the actuator bar to the arm by the link 64 over making the arm 58 integral with the actuator bar 47.

The link 64 has half round ends 73 and

74 fitting in seats and the link is just long enough to sustain the pressure of the actuator bar 47 toward the arm 59 and relieve the friction between the faces 75 and 76. The edge 48 of the actuator bar 47 is longer 70 and more inclined than could be made directly upon the arm 59 and at the same time get the desired amount of swing.

Various changes may be made without departing from the spirit of my invention as 75 claimed.

I claim:

1. An actuator for silent railway crossings comprising the combination with a rail, 80 of an actuator mounting having an attaching plate secured against the inner side of the rail, a ledge extending inwardly from the upper part of the attaching plate, an actuator bar pivotally connected to the ledge at a point inside of the wheel flange groove 85 and adapted to extend diagonally across the wheel flange groove to the rail, and a lever pivotally attached to the ledge and having an arm extending inwardly and adapted to be connected to the crossing mechanism and 90 having a second arm extending outwardly on a diagonal line and adapted to be operated by the actuator bar.

2. An actuator for silent railway crossings comprising the combination with a rail, 95 of an actuator mounting having an attaching plate secured against the inner side of the rail, a ledge extending inwardly from the upper part of the attaching plate, an actuator bar pivotally connected to the ledge 100 at a point inside of the wheel flange groove and adapted to extend diagonally across the wheel flange groove to the rail, a lever pivotally attached to the ledge and having an arm extending inwardly and adapted to be 105 connected to the crossing mechanism and having a second arm extending outwardly on a diagonal line, and a link connecting the free end of the actuator bar to the free end of the second arm.

3. A silent railway crossing having shifting treads movable in lines diagonally across the rails at the rail junctions, an actuator mounting having an attaching plate secured against the inner side of the rail, a ledge 115 extending inwardly from the upper part of the attaching plate, an actuator bar pivotally connected to the ledge at a point inside of the wheel flange groove and adapted to extend diagonally across the wheel flange 120 groove to the rail, a lever pivotally attached to the ledge and having an arm extending inwardly and connected to the shifting treads and having a second arm extending outwardly on a diagonal line, and a link 125 connecting the free end of the actuator bar to the free end of the second arm.

4. An actuator for silent railway crossings including the combination with a rail 130 of an actuator mounting at the inner side

of said rail and secured thereto, an actuator bar pivoted to said mounting at a point inside of the wheel flange groove of said rail and adapted to extend diagonally across 5 the wheel flange groove to the rail tread, and a lever pivotally attached to said mounting and having an arm extending in-

wardly and adapted to be connected to the crossing mechanism and having a second arm adapted to be operated by the actuator bar.

In testimony whereof I have signed my name to this specification.

RICHARD ROTHWELL.
